SHOEMAKING METHOD

George E. Musebeck, Danville, Ill., assignor to
Musebeck Shoe Company, Danville, Ill., a cor-
poration

Application January 8, 1940, Serial No. 312,886

2 Claims. (Cl. 12—147)

This invention relates to an orthopedic shoe especially adapted for women's wear and a method of manufacturing the same.

In the manufacture of orthopedic shoes for women great difficulty has been encountered in providing the necessary strength and stiffness in a shoe sufficiently light in weight for women's wear. If the shoe is sufficiently strong to have the desired orthopedic effect it is ordinarily heavy enough to be very tiring to the wearer. The greater part of the weight is found in the heavy orthopedic outsole and the leather heel lift commonly employed. The use of lighter wooden heel lifts for women's orthopedic shoes has not heretofore been successful due to the fact that the heavy pressure required to make the outsole and insole conform to the shape of the upper face of the heel lift when placed in a heelng machine are too great for a wooden lift to withstand and considerable breakage results. Such conformity is necessary, otherwise portions of the outsole and insole are not rigidly supported by the heel lift and tend to collapse in the use of the shoe, and the rear end of the metallic shank stiffener 25 extending into the heel portion of the shoe is not rigidly held in place and tends to work up and down in the use of the shoe.

Even with leather heel lifts it is difficult to conform a heavy orthopedic outsole to the upper surface of the heel lift and it has been found necessary to reduce the width of the outsole above the heel lift to make such conformity possible. Such reduction introduces a point of weakness at the breast of the heel. The difficulty of conforming the outsole to the heel is increased by the fact that the work can ordinarily not be done while the outsole is in temper, otherwise the drying of the outsole causes it to check away from the heel lift and cause unsightly cracks between the two.

One object of the present invention is to produce a light weight orthopedic shoe having the strength and orthopedic qualities of heavier shoes found in the prior art.

Another object of the invention is to overcome the difficulties in conforming outsole to heel lift.

Another object of the invention is to produce the necessary rigidity for the heel portion of the shoe without the application of sufficient pressure to break a wooden heel lift.

Reduction in weight without sacrifice of strength is obtained by the use of a wooden heel lift instead of a leather lift, by reducing the thickness of the outsole in the shank and heel portion and anchoring the shank stiffener so firmly in

the heel portion of the shoe that the tendency of the shank to spring is substantially eliminated. The strength added by the rigid anchorage of the shank stiffener compensates for the reduced weight of the outsole in the shank portion. The new method of securing rigid support for the outsole on the heel lift hereinafter described makes it unnecessary to reduce the width of the heel portion of the outsole. The outsole substantially covers the area of the heel lift and the point of weakness at the breast of the heel is thereby eliminated. By these changes a shoe weighing 14 ounces has been reduced to 10½ ounces in weight, a reduction of twenty-five percent.

The necessary support for the outsole on the heel without sufficient pressure to break a wooden heel lift is secured by, first, securing the heel while the outsole is still in temper and relatively pliable and finishing the edge of the outsole so that no unsightly cracks can be formed by subsequent checking, and second, by filling whatever interstices remain between the outsole and heel with a fluid or semi-fluid material adapted to harden and give a rigid support. Preferably said material is a liquid glue and is injected under pressure through a suitable opening in the heel lift.

Other objects and features of the invention will be readily understood from the accompanying drawing and the following description and claims:

Fig. 1 is a side view of the lower portion of a shoe construction in accordance with the invention. Fig. 2 is a bottom view of the sole of said shoe with the positions of the several rows of stitching shown in broken lines. Fig. 3 is a sectional view taken on the lines 3—3 of Figs. 1 and 2 with the parts shown in an abnormally spaced relation for the sake of clearness. Fig. 4 is a sectional view on the line 4—4 of Fig. 2 showing the heel construction.

In the preferred form of the invention shown in the drawing by way of illustration, there is provided an outsole 10, insole 11 and upper 12. The insole is preferably formed in accordance with my prior Patents 1,916,198 and 1,850,977. The thickness of the outsole is relatively heavy forward of the point A in Fig. 1 and considerably lighter to the rear of that point. The insole is provided with a common form of Goodyear stitching channel 13 about the edge of the forward and shank portions thereof. A welt 14 lies beneath a feather 15 formed in the insole. The insole 11, upper 12 and welt 14 are secured together about the forward and shank parts of the shoe by a line of Goodyear stitching 16. The

outsole 10 is secured to the welt 14 by a row of stitching 17 co-extensive with the welt.

The usual shank stiffener 19 is also employed between the insole and outsole in the shank of the shoe and extends into the heel portion as seen in Fig. 4.

A heel lift 20, preferably of wood or some similar light weight material, is formed with a central opening 21 extending vertically therethrough 10 and is secured by nails 22 extending completely through the heel lift, outsole and insole and clinched on the upper surface of the insole.

In the manufacture of the shoe the outsole is formed with the edge of the heel portion unfinished and of proper size to extend slightly beyond the edges of the heel lift. The upper, insole, outsole, shank stiffener and welt are lasted in the usual manner, the outsole being tempered prior to the lasting operation. The heel lift is 20 then clamped to the shoe structure with as great a pressure as may be applied without danger of breaking the same. The heel lift is secured by the nails 22 while the outsole is still in temper. The outsole, therefore, conforms more readily to 25 the upper face of the heel lift than if it were allowed to dry before securing the heel. The danger of formation of unsightly cracks between the outsole and heel by subsequent checking is eliminated by finishing the outer edge of the sole 30 about the heel portion after assembly. This operation is performed by a special cutter 23 shown in Fig. 1 which forms the outer edge of the outsole into a rounded bead, leaving a groove 24 at the junction of the outsole and heel. Whatever 35 cracks may later appear are at the base of the groove 24 and are invisible. The bead itself produces a pleasing ornamental effect.

The difficulty of conforming the outsole to the upper surface of the heel lift is increased by the 40 use of a shank stiffener covering a portion of the heel. Even when the heel is secured to the shoe while the outsole is in temper some openings will remain between the insole and outsole about the edge of the shank stiffener and between the outsole and heel. In order to eliminate such openings and to provide rigid support for the heel of the foot over its entire area, the opening 21 in the heel lift is partially filled with a liquid glue while the shoe is in an inverted 45 position. A closely fitting plug 25 is then driven into the opening and forces the glue under hydraulic pressure between the outsole and heel. The glue 26 when it hardens, forms a rigid support for the outsole wherever the outsole is not in 50 actual contact with the heel lift and the hy-

draulic pressure forces the outsole upwardly into definite supporting relation to the insole. While liquid glue is preferred, any other material adapted to flow under pressure and to harden may be used. The usual rubber top lift 27 may 5 then be added to the shoe.

The shoe constructed as just described has no point of weakness at the breast of the heel since the width of the outsole is not reduced. The shank stiffener is firmly supported at its rear end 10 on a surface accurately conforming to its under surface and is firmly pinioned between the insole and outsole. Any tendency for the shank stiffener to work up and down in the use of the shoe is substantially eliminated. The rigid anchorage of the rear end of the shank stiffener also eliminates tendency of the shank portion to spring vertically and thus more than compensates for the reduced thickness of the outsole in that portion of the shoe. 20

The invention has been described in one of its preferred forms, the details of which may be varied by those skilled in the art without departing from the scope of the invention as defined by the appended claims. 25

The invention claimed is:

1. In a method of making a shoe having a heel lift, an outsole having a portion above said heel lift, and an insole, the steps of forming an opening through said heel lift communicating with the upper surface thereof, securing together said heel lift, outsole, and insole, filling said opening at least partially with a fluid or semi-fluid material adapted to harden, and driving a closely fitting plug into said opening to inject said material under pressure into interstices between said heel lift and outsole prior to hardening, said material after hardening forming a rigid support for said outsole. 35

2. In a method of making a shoe having a heel lift, an outsole having a portion above said heel lift, a shank stiffener extending over said heel lift, and an insole, the steps of forming an opening through said heel lift communicating with the upper surface thereof, securing together said heel lift, outsole, shank stiffener and insole, filling said opening at least partially with a fluid or semi-fluid material adapted to harden, and driving a closely fitting plug into said opening to inject said material under pressure into interstices between said heel lift and outsole prior to hardening, said material after hardening forming a rigid support for said outsole and shank stiffener. 50
